UNITED STATES PATENT OFFICE.

HAROLD A. BOXILL, OF CINCINNATI, OHIO.

GRINDING-MACHINE.

1,169,231.

Specification of Letters Patent. Patented Jan. 25, 1916.

Application filed April 9, 1915. Serial No. 20,212.

To all whom it may concern:

Be it known that I, HAROLD A. BOXILL, a subject of the King of Great Britain, residing at Cincinnati, county of Hamilton, 5 and State of Ohio, have invented certain new and useful Improvements in Grinding-Machines; and I do hereby declare that the following is a full, clear, and exact description thereof.

10 My invention relates to that class of grinding machines especially adapted for grinding engine cylinders and in which a grinding member is simultaneously rotated and revolved around the axis of the cylinder in contact with the wall and fed longitudinally thereof.

One object of the invention is to provide simple and efficient means for effecting these movements simultaneously, means for rotating the grinding member independently of the operation of the revolving and feeding mechanism so that the speed of rotation of the grinding member is not dependent upon the speed of revolution; and to provide means for simultaneously revolving and rotating the grinding member without moving it longitudinally.

Another object of the invention is to provide a structure wherein the grinding wheel 30 spindle and its supporting and actuating parts are moved longitudinally as a unit whereby the rigidity of the spindle is maintained throughout its travel along the wall of the cylinder, and chattering of the grinding wheel is entirely eliminated.

The invention consists in the construction, combination and arrangement of parts as hereinafter described and claimed.

In the accompanying drawings—Figure 40 1 is a longitudinal vertical section of a machine embodying my invention. Fig. 2 is a side elevation seen from the left of Fig. 1. Fig. 3 is a top view, with the gear cover and grinding motor removed. Fig. 4 is a detail 45 sectional view illustrating a centering device. Fig. 5 is an enlarged vertical section of a current collector for the grinding motor. Fig. 6 is a perspective view of the support for the latter. Fig. 7 is a plan view 50 of the current collector with the cover removed.

1 designates a cylindrical housing adapted to be accurately alined on a separate base member 2 by means of male and female 55 flanges 3, 4, formed on the housing and base

respectively, said flanges being connected by bolts 5.

Journaled in the housing 1 and projecting through both the housing and base is a cylindrical sleeve 6 having an annular rack 60 7 formed on its outer periphery substantially throughout its entire length. This sleeve 6 has a longitudinal cylindrical bore 8 formed eccentrically therein and in said bore is mounted a bearing bar or tube 9 65 adapted to be rotated in the bore for the purpose of adjustment and locked therein by screws 10 which project through the sleeve 6 and engage annular grooves 11 formed in the periphery of the bearing bar. 70

A spindle 12 extends through the bearing tube 9 and is journaled therein eccentric to the axis of the tube in ball bearings 13 suitably fixed in each end of the tube. The tube is closed by plates 14 screwed onto the 75 ends of the tube. The ends of the spindle are reduced to form shoulders which abut against the housing of the ball-bearings so that longitudinal movement of the spindle relatively to the bearing tube is prevented. 80

The sleeve 6 is raised and lowered in the housing 1 by means of a gear 15 projecting through the side of the housing and engaging the annular rack 7. Said gear is journaled in an arm 16 formed on the housing, 85 and meshes with a worm 17 fixed on a horizontal shaft 18 journaled in a bearing 19 formed in the upwardly turned end of the arm 16. On the shaft 18 is rotatably mounted a worm gear 20 having a clutch 90 face 21 on one side adapted to be engaged by a clutch face 22 formed on the side of a clutch member 23 which is connected to said shaft by a feather 24 to permit axial movement of the member thereon. For the purpose of rotating the shaft 18 by hand to bring the sleeve into operative position, said shaft has a squared end portion 25 for the reception of a crank 26, (Fig. 2). When the machine is in operation, the shaft is driven 100 from an electric motor and is connected by the clutch member 23 to the worm gear 20, the latter being driven by a worm 27 on one end of a shaft 28. The latter is mounted transversely to the shaft 18, in bearings 29, 105 (Fig. 3) formed in a bracket 30 which is connected to the top of bearing 19 by bolts 31. On the other end of shaft 28 is fixed a worm gear 32 (Fig. 2) meshing with a worm 33 fixed on a power shaft 34 which 110

is journaled in a bearing 35 on the outer end of the bracket 30. This power shaft extends parallel to shaft 18 through a casing 36 connected by bolts 36' to the upper part of the housing 1. This casing provides additional journals for the shaft 34 which is connected at its other end by a flexible coupling 37 to the shaft of an electric motor 38 which is mounted on a support 39 detachably connected to a horizontal arm 40 extending outward from the housing 1. Rotation of the sleeve 6, (and by it a revolution of the tube 9 and spindle 12) is imparted from the shaft 34 by means of a worm 41, fixed on the latter between its ends, meshing with a large horizontal worm gear 42, which surrounds the sleeve 6 and is so connected to the latter as to permit longitudinal or axial movement of the sleeve. The gear 42 is rotatably mounted on the housing by means of its downwardly projecting hub 43 which is seated in an annular recess formed in the upper end of the housing. To prevent axial displacement of the gear, it is connected to the housing by a divided ring 44, secured to the side of the housing by screws 45 and having a horizontal flange taking into a groove formed in the periphery of the hub 43.

The connection between the gear 42 and sleeve 6 consists of a key or feather 46 on the interior of the hub 43 taking into a keyway 47 formed through the teeth 7 longitudinally of the sleeve. This connection permits a free longitudinal movement of the sleeve through the gear and prevents relative rotation between the sleeve and gear.

A grinding disk 48 is detachably fixed, by any suitable means, on the lower end of the spindle 12. As above stated, the spindle is eccentric to the axis of the bearing tube 9, which is eccentrically and adjustably mounted in the sleeve 6. For the purpose of rotating the bearing tube in the sleeve, to vary the degree of eccentricity of the spindle relative to the axis of the sleeve, the top end plate 14 of the bearing tube is provided with holes 49 adapted to receive a well known form of spanner wrench. When the bearing tube has been so positioned that the grinding disk will engage the wall of the cylinder to be ground, said tube is locked in the sleeve by the screws 10.

The spindle 12 is driven by an electric motor 50 mounted on a stand 51 secured by bolts 51' to the top end plate 14; the spindle being connected to the motor shaft by a flexible coupling 52. By the aid of graduations 53, (Fig. 3) on the upper end of the sleeve 6, and an index finger 54 on the motor stand, the degree of eccentricity of the spindle relative to the axis of the sleeve 6 may be readily ascertained. As the motor 50 revolves around the axis of sleeve 6 and moves up and down with the latter, a current col-

lector adapted to partake of these movements is provided to supply current to the motor. This collector consists of a fiber disk 55, (Figs. 5 and 7) adapted to be connected by screws 55' to the rotating elements 70 of the motor, said disk having a central contact plate 56 and an annular contact plate 57 surrounding the latter. Lead wires (not shown) are connected, by binding screws 58, to these contacts and pass through holes 75 59 to the motor. The fiber disk rotates in a cover 60 to which it is connected by an anti-friction coupling consisting of balls 61 mounted in grooves 62, 63, formed respectively in the outer periphery of the disk 55 80 and in the side of the cover 60, the balls being introduced into the grooves through a hole in the cover closed by a screw 64. While the cover is free to revolve with the motor, it is prevented from rotating with the disk by an arm 65 projecting from the cover and reciprocably connected by a bearing 66 to a standard 67 mounted on the cover of the gear casing 36. The cover 60 carries contact brushes 68 yieldingly connected to binding 90 posts 69 and resting on the contacts 56, 57, said brushes and posts being insulated from the cover by bushings 70.

In Fig. 4 I have illustrated a convenient means for accurately centering the base 2 on 95 the engine cylinder to be ground. The base 2 is placed on top of the engine cylinder 71 and a second cylinder, having a cylindrical portion 72 of substantially the same diameter as the base, and a conical end portion 73, 100 is inserted in the base and pushed into the engine cylinder until the end 73 engages the bore of the latter at all points. The base is then securely fastened onto the engine cylinder by passing bolts 74 through the bolt 105 holes of the cylinder and through elongated slots 75 formed in the lower flange 76 of the base. The centering cylinder is then removed and the housing 1 centered on the base by means of the male and female 110 flanges 3 and 4 of the housing and base.

Before the grinding operation is started, the worm gear 20 is disconnected from the shaft 18 by moving the clutch member out of engagement with said gear. The shaft 18 115 is then rotated by means of the crank 26 to actuate the gear 15 to lower the cylindrical rack 7 into position for positioning the grinding disk 48 at the top of the engine cylinder. The bearing tube 9 is rotated in 120 the sleeve 6 until the disk 48 contacts with the cylinder, the rotation being brought about by first loosening the screws 10 when the tube may be rotated by a spanner wrench placed in the holes 49 in the top plate 14. 125 When the parts are in position, the tube is locked to the sleeve 6, and the gear 20 locked to the shaft 18. Simultaneous revolution and longitudinal movement of the sleeve 6 is effected from the shaft 34, the worm 130 41 133

thereon meshing with the teeth of gear 42, the worm 33 of said shaft meshing with worm gear 32 on shaft 28, worm 27 on the latter meshing with gear 20 which is now locked to shaft 18, the worm 17 of which engages gear 15.

The spindle 12 is rotated, during its revolution and longitudinal movement, by the electric motor 50 which may be driven at any desired speed. If it is desirable, for any reason, to stop the longitudinal feed, this can be done by simply moving the clutch member 23 out of engagement with the gear 20.

15 I claim—

1. In a machine for grinding cylinders, a cylindrical housing, a cylindrical member therein, means to rotate the member, means to simultaneously or independently feed the member longitudinally, a grinding wheel spindle mounted in said member and movable therewith, means to adjust the spindle parallel to the axis of said member, and independent means for rotating the spindle.

25 2. In a machine for grinding cylinders, a cylindrical housing, a cylindrical member therein, means to rotate the member, means to automatically continuously feed the latter longitudinally either simultaneously or independently of its rotation, a grinding wheel spindle mounted in said member and movable longitudinally therewith, means to adjust the spindle parallel to the axis of said member, and independent means for rotating the spindle.

35 3. In a machine for grinding cylinders, a cylindrical housing, a cylindrical member mounted therein, means to rotate the member, means to simultaneously or independently feed the member longitudinally, a grinding wheel spindle mounted eccentrically in said member and movable therewith, independent means for rotating the spindle movable therewith and means for adjusting the eccentricity of the spindle and its rotating means with respect to the cylindrical member.

45 4. In a machine for grinding cylinders, a cylindrical housing, a cylindrical member rotatable and longitudinally movable in the housing, a bearing tube mounted eccentrically in the cylindrical member and movable therewith, a grinding wheel spindle journaled eccentrically in the bearing tube and movable therewith, means for rotating the cylindrical member, means to move the latter longitudinally, and means to rotate the spindle.

5. In a machine for grinding cylinders, a cylindrical housing, a cylindrical member rotatable and longitudinally movable in the housing, a bearing tube mounted eccentrically in the cylindrical member and movable therewith, a grinding wheel spindle journaled eccentrically in the bearing tube and

movable therewith, means for rotating the cylindrical member, means to move the latter longitudinally, means to connect the rotating and moving means, and means to rotate the spindle.

6. In a machine for grinding cylinders, a cylindrical housing, a cylindrical rack rotatable and longitudinally movable in the housing, a bearing tube adjustably mounted eccentrically in the rack, means to lock the tube in the latter, a grinding wheel spindle journaled eccentrically in the tube and held against longitudinal movement relative thereto, means for rotating the rack, independent means for longitudinally moving the latter, means to connect the rotating means to the moving means, and independent means for rotating the spindle.

7. In a machine for grinding cylinders, a cylindrical housing, a cylindrical rack rotatable therein, a gear surrounding the rack, means connecting the gear and rack adapted to permit the latter to move axially of the gear and to prevent independent relative rotation of said rack and gear, means to rotate the latter, independent means for axially moving the rack, means to connect the rotating and moving means, a grinding wheel spindle eccentrically journaled in the cylindrical rack and axially movable by the latter, and means to rotate the spindle.

8. In a machine for grinding cylinders, a cylindrical housing, a cylindrical rack rotatable therein, a gear surrounding the rack, means connecting the gear and rack adapted to permit the latter to move axially of the gear and to prevent independent relative rotation of said rack and gear, means for axially moving the rack through the gear, means for rotating the gear adapted to actuate the moving means, and an electric motor carried by the cylindrical rack adapted to rotate the spindle.

9. In a machine for grinding cylinders, a cylindrical housing, a cylindrical rack rotatable therein, a gear surrounding the rack adapted to rotate the latter, means to move the rack through the gear during rotation of the gear, a bearing tube mounted eccentrically in and movable with the rack, a grinding wheel spindle journaled eccentrically in the tube and axially movable with the latter, an electric motor mounted on the tube, and a flexible coupling connecting the motor and spindle.

10. In a machine for grinding cylinders, a cylindrical housing, a cylindrical rack rotatable therein, a gear engaging the rack adapted to raise and lower the latter, a worm shaft for driving the gear, a gear loose on the shaft, means to clutch the loose gear to the shaft, an electric motor, a power shaft connected to the motor shaft, gearing connecting the power shaft to the loose gear, means for rotating the rack, a grinding

wheel spindle eccentrically mounted in the latter and movable longitudinally thereby, and means for rotating the spindle.

11. In a machine for grinding cylinders, a cylindrical housing, a cylindrical rack rotatable therein, a gear engaging the rack adapted to raise and lower the latter, a worm shaft for driving the gear, a gear loose on the shaft, means to clutch the loose gear to the shaft, an electric motor, a power shaft flexibly connected to the motor shaft, gearing connecting the power shaft to the loose gear, a driving gear surrounding the rack, a connection between the driving gear and rack adapted to rotate the latter and permit axial movement thereof independent of the driving gear, a worm on the power shaft in mesh with the driving gear, a bearing tube mounted eccentrically in the rack, a grinding wheel spindle journaled eccentrically in the tube and axially movable with the latter, an electric motor mounted on the tube, and a flexible coupling connecting the last named motor to the spindle.

12. In a machine for grinding cylinders, a cylindrical housing, a cylindrical rack rotatable therein, a gear engaging the rack adapted to raise and lower the latter, a worm shaft for driving the gear, a gear loose on the shaft, means to clutch the loose gear to

the shaft, an electric motor, a power shaft flexibly connected to the motor shaft, gearing connecting the power shaft to the loose gear, a driving gear surrounding the rack, a connection between the driving gear and rack adapted to rotate the latter and permit axial movement thereof independent of the driving gear, a worm on the power shaft in mesh with the driving gear, a bearing tube mounted eccentrically in the rack, a grinding wheel spindle journaled eccentrically in the tube and axially movable with the latter, an electric motor mounted on the tube, and a flexible coupling connecting the last named motor to the spindle.

In testimony that I claim the foregoing as my invention, I have signed my name, in presence of two subscribing witnesses.

HAROLD A. BOXILL.
